ALARM WATER COLUMN

Walter J. Kinderman, Philadelphia, Pa., assignor
to Yarnall-Waring Company, Philadelphia, Pa.,
a corporation of Pennsylvania

Application February 8, 1937, Serial No. 124,676

11 Claims. (Cl. 137—102)

The invention relates to alarm water columns which operate when the water level in a boiler or the like is abnormally high or abnormally low.

A purpose of the invention is to obtain greater sensitiveness in the operating mechanism of a water column, so as to enable the operating mechanism to function at higher pressures and on smaller changes in water level at any given pressure.

10 A further purpose is to locate in the same line, the fulcrum of the operating lever and the weight suspension pivots toward the ends of the lever.

15 A further purpose is to locate the center of the actuating pin, engaging the valve stem yoke of an alarm water column mechanism, in or very near the line including the lever fulcrum and the weight suspension pivots, and closely adjacent the fulcrum.

20 A further purpose is to shorten the levers of an alarm water column to permit the use of columns of smaller diameter.

25 A further purpose is to space the levers of an alarm water column by lugs that curve convexly to the fulcrum, so that the moments of lateral frictional engagements of the levers will approach zero.

30 A further purpose is to improve and simplify the T rod connection to the chains of an alarm water column.

35 Further purposes appear in the specification and in the claims.

In the drawings one embodiment and a minor variation thereof are shown, by way of example, choosing the form illustrated mainly from the standpoints of satisfactory operation and convenient explanation of the principles involved.

Figure 1 is a sectional side elevation of a desirable embodiment of the alarm water column gauge.

40 Figure 2 is an enlarged front elevation of the operating mechanism showing the supporting cap in section and omitting the water column body and the gauge.

45 Figure 3 is an enlarged top plan view of the levers in position and showing the valve stem yoke in dot and dash.

Figure 4 is a section of Figure 3 on the line 4—4 thereof in the direction of the arrows.

50 Figure 5 is a detail top plan view of the valve step yoke, being a section upon the line 5—5 of Figure 6 in the direction of the arrows.

55 Figure 6 is a side elevation of the valve stem yoke of Figure 5.

Figure 7 is a fragmentary section of the end of the T rod.

Figure 8 is a section of Figure 4 taken upon the line 8—8 thereof and to indicate a low-friction feature.

Figure 9 corresponds to Figure 8 but in somewhat different form.

Figures 10 and 11 are diagrammatic elevations of the structures of the prior art and of the invention respectively.

In the drawings like numerals refer to like parts.

10 Describing in illustration and not in limitation and referring to the drawings:

In steam boilers and similar devices, it is conventional practice to employ a water gauge to indicate the water level, and mechanism adjoining the gauge for operating an alarm such as a whistle in case the water level reaches an abnormally high or abnormally low level. In such alarm water columns of the prior art, difficulty has been encountered through lack of sensitiveness which has resulted in limiting the use of such alarm water columns to low pressures, or rendering them less certain of operation at high pressures, and in rendering them insensitive to a small change in water level. The present invention seeks to increase the sensitiveness from both standpoints.

15 In prior devices, the weight suspension pivots at the ends of the levers have been located on a line (assuming any lever to be horizontal) usually considerably below the fulcrum, resulting in variant sensitiveness in different water column positions. In the present invention, sensitiveness has been increased and made uniform by bringing the weight suspension pivots and the fulcrum 20 substantially into line.

25 In prior constructions, the pin engaging in the valve stem yoke has been placed ordinarily in the vertical center of the lever and opposite the center of the opening in which the knife edge for the lever fulcrum is placed. In accordance with the present invention, the actuating pin is placed so that its center is on or close to a line connecting the high and low weight supporting knife edges which line passes through or very close to the lever fulcrum knife edge. This permits locating the actuating pin much closer to the lever fulcrum knife edge than in the prior art construction, and, by greatly decreasing the lever arm of the actuating pin, correspondingly greatly increases the mechanical advantages at which the weights act upon the actuating pin. This has 30 caused increased sensitiveness in the present invention, and has permitted a shortening of the levers and a use of smaller water column casings 35

55

Figure 4 is a section of Figure 3 on the line 4—4 thereof in the direction of the arrows.

Figure 5 is a detail top plan view of the valve step yoke, being a section upon the line 5—5 of Figure 6 in the direction of the arrows.

Figure 6 is a side elevation of the valve stem yoke of Figure 5.

Figure 7 is a fragmentary section of the end of the T rod.

at the same or higher pressures, with resulting great economy.

In prior water alarm columns, the circular boss on the lever around the opening receiving the 5 knife edge fulcrum was employed for spacing the levers. A considerable part of the engaging surface of the boss was at a relatively great distance from the fulcrum, so that its friction acted on a relative long lever arm. In the present invention, 10 spacing lugs are located to curve convexly to the knife edge so that the frictional engaging surfaces of the levers are minimized.

By the cooperative use of the different features 15 of the present invention, the device has been found to operate well with test pressures up to 1500 pounds per square inch with every appearance that it will be successful at much higher pressure. Formerly the corresponding mechanism was limited to about 700 pounds per square inch. 20 The features of the present invention have also made it possible to open the valve at a change in water level of about three-eighths of an inch at 350 pounds per square inch pressure, where the prior art device required a change in water level 25 of one inch for opening at this pressure. At 1500 pounds per square inch the valve in the alarm column of the present invention will open at a change in water level of about one inch. No figure is available for the prior art device at this pressure.

In the structure of Figures 1 to 8 the water column casing 10 presents flanged openings at 11 and 12 that connect into a boiler or the like, not shown, and at points respectively above and 35 below the water level in the boiler, and presents flanged connections at 13 and 14 to any suitable water gauge 15. Valves are indicated at 16 and 17 for use with the gauge 15 and a usual drain connection is shown at 18.

40 The operating mechanism of the water column is carried upon a cap 19 which cap is bolted at 20 to position against suitable lugs 21 of the body.

Laterally spaced downward lugs 22 from the 45 inner face of the cap are formed to support the opposite ends of the lever fulcrum 23 and the levers 24 and 25 balance upon the knife edge 26 of the fulcrum 23.

The levers 24 and 25, preferably opposite counterparts, present actuating pins 27 and 28 into 50 oppositely directed horizontal slots 29 and 30 of a valve stem yoke 31, the actuating pins 27 and 28 being near to and spaced from opposite sides of the knife edge 26, the middle of the center 55 line between the pins suitably being in or very near the common pivotal axis of the levers.

This yoke 31 at its lower arms spans the fulcrum 23, and at 32, vertically above the knife edge, pivotally connects to the valve stem 33. The 60 tapered end 34 of the needle valve at the upper end of the stem 33 controls the discharge and non-discharge of steam through an opening 35 to a high or low water alarm whistle 36, which may be any suitable steam whistle.

65 The whistle 36 threads at 37 into the casing 38 of the valve mechanism, which casing threads at 39 into a central opening through the cap 19.

High and low weights 40 and 41 are suspended by the levers 24 and 25, the actuating-pin ends of 70 the levers 24 and 25 supporting the low weight at low-weight suspension pivots 42 and the ends of the levers 24 and 25 away from the actuating pins 27 and 28 supporting the high weight at high-weight suspension pivots 43.

75 The high weight 40 is suspended by chains

44 between the high-weight suspension pivots 43 and opposite sides of the high weight 40. These chains 44 pass downward through side perforations 45 of the high weight, and adjustably support the weight 40 at pins 46 under the weight. 5

The low weight 41 is carried by a T rod 47, the vertical portion of which adjustably axially threads the low weight at 48, with lock nuts at 49, passes upwardly through a central perforation 50 of the high weight and from opposite 10 ends of the T bar 51 is itself suspended by low-weight suspension chains 52 to the low-weight suspension pivots 42.

To permit wider relative adjustment of the high and low weights, the T bar 51, which limits 15 the high position of the high weight, is located preferably fairly close to the supporting levers, and a feature of the present invention is directed to a connection between the T bar ends and bottom links of the low-weight-suspension chains 52, 20 for maintenance of the precisely uniform spacing of the chains from one another at their lower ends at a distance for minimum friction and minimum change of moment at the supporting low-weight suspension pivots 42. 25

As illustrated in Figure 7, each end of the T bar is bored at 53, beveled at 54 and receives a pivot pin 55 through the bottom link of the suspension chain 52. The pivot pin 55 is located longitudinally so that the opposing bevel surfaces 30 of the pin head and of the bar end at 54 prevent lateral play of the chain and permit very close clearance between the end of the pin and the interior wall of the water column casing 10. The pivot pin 55 suitably is held to position by a key 56. 35

A number of the features of the invention are directed to an increase in the delicacy and uniformity of indications of the device even with quite widely different pressures.

As indicated in Figure 4 I locate the weight 40 suspension pivots at 42 and 43 so that a line 57 joining their axes crosses the lever pivot 23 substantially at the knife edge 26 and also locate the actuating pins 27 and 28 close to the lever axis, suitably with their center lines up to or 45 above the line 57 joining the suspension pivotal axes.

The low-weight suspension pivots 42 and the high-weight suspension pivots 43 each comprise knife edges 42' or 43' engaging the upper edges 50 of the openings of hangers 52' or 44' which connect to the chains 52 or 44.

To reduce to a minimum friction from axial play of the levers 24 and 25 I limit such movement by engagement surfaces that curve 55 convexly to the lever fulcrum.

In Figures 3, 4, and 8 these surfaces are shown at 58 and 59 at the end of lug extensions 60 and 61 from opposite sides of each lever, the surfaces in each case convexly curving to the pivotal axis 60 of the lever. In Figure 9 these surfaces are on ball members 62, 63, and 64 rigidly fastened to the knife edge member 23 in suitable recesses thereof, by pins 65 and in such manner that the ball centers are at the lever fulcrum. 65

It will be understood that in this type of high and low alarm water column, the operation depends on changes in the buoyancy forces upon the weights when the water level in the column changes, each weight being buoyed by a force 70 equal to the weight of fluid that it is displacing, this fluid being steam or water or part water and part steam.

Assuming the water level to be located between the weights, the downward pull of the low weight 75

is reduced by a buoying force equal to the weight of the low weight's volume of hot water and the downward pull of the upper weight is reduced by a buoying force equal to the weight of the high weight's volume of steam.

In normal position the levers are at rest in position to hold the needle valve closed, this being the position at which the low-weight suspension pivots 42 are in their high position and the high-weight suspension pivots 43 in their low positions, the totally submerged and upwardly buoyed low weight being over-balanced by the high weight buoyed merely by steam.

If the water rises to the high weight 40, a further rise progressively increasingly buoys the high weight and thereby progressively reduces its downward pull until, when the water level is at some point vertically intermediate the high weight's height, the downward pull of the high weight is over-balanced by that of the wholly submerged lower weight, the levers shifting to their open-valve positions. The steam then operates the whistle until the water level has fallen sufficiently to let the low weight again overbalance the high weight to close the valve.

In similar way if the water progressively falls below the top of the low weight, its pull upon the balance progressively increases until it overbalances the upper weight to operate the whistle as above described.

Diagrammatic Figures 10 and 11 are intended to bring out the relative advantages of structures of the prior art and of the present invention. These are not intended as showings of complete structures.

Figure 10 is intended to represent commercial structure of the prior art such as has been and still is widely used, and Figure 11 is intended to represent the structure of the invention, as already described. In both figures, one weight-supporting lever only is shown, since these levers are opposite counterparts and the operation of either is that of the other, except that they are oppositely placed with respect to the lever fulcrum 23 for joint action on the valve stem yoke.

In the diagrams the high and low weights 40 and 41 or 40' and 41' are shown laterally offset from the lever pivot and suspended from and directly below the high-weight and low-weight suspension pivots 43 and 42 respectively in Figure 11 and 43' and 42' respectively in Figure 10. These weights however are intended to correspond actually in general to the high and low weights 40 and 41 of Figure 1, since they are intended to be in practice directly beneath the lever fulcrum 23 and each supported by oppositely directed ends of two levers.

In the prior art structure of Figure 10, the lever 25' is of generally diamond-shaped contour and bored along its longitudinal axis at 66, 67, 68, and 69 respectively to pass the lever fulcrum 23', to receive the actuating pin 27', to make loose pin connection with the low weight 41' and loose pin connection with the high weight 40'. As intended to be typical of prior art structure, the lines 70 and 71 respectively from the pivotal axis 26' to the low-weight suspension axis 42' and to the center of the actuating pin 27' are intended to make angles of, for example, 7½° and 29½° respectively with the longitudinal axial line 72.

The pivotal axis at 26' of the lever is located well above its longitudinal axial line 72, that has been made the line of centers of the bores 66, 67, 68, and 69 and both the upward offsetting 73 of the pivotal axis at 26' with respect to the sus-

pension pivots 42' and 43' and the downward offsetting 73 of the actuating pin 27' with respect to the pivotal axis have been considered advantageous as together providing for an easy accommodation of the device to different operating conditions by merely selectively varying the normal valve-closed position of the lever, as determined by suitable selection of the position for valve closure. In this way suitable adjustment is made between the effective lengths of lever arms of the low and high weights and also of that of the valve mechanism operating at the actuating pin 27' and also of the valve-opening moment exerted at the normal valve-closed position by the lever's own weight.

The normal valve-closed position of the lever can be selectively varied by having the low weight suspension pivot 42' in the valve-closed position selectively anywhere between some distance below to some distance above a horizontal line 74 through the lever pivot axis at 26'.

It will be seen that progressive shifting of the normal valve-closed position will make material progressive change in the moment arm of the high weight 40' with but little change in the moment arm of the low weight 41'; will make material change in the moment arm of the lever itself, that is in the horizontal offsetting 75 of the lever's own center of gravity from the lever axis 26'; and will make material change in the moment arm of the weight of the valve mechanism 33' applied at the actuating pin 27'.

For example in Figure 10, assuming the 7½° and 29½° construction angles above, if the valve seat 76 were vertically shifted to shift the valve-closed position of the low weight suspension pivot from 7½° below to 7½° above the horizontal line 72, then the arm ratio of the low and high weights would shift from $\cos 7\frac{1}{2}^\circ / \cos 7\frac{1}{2}^\circ$ or 1 to $\cos 7\frac{1}{2}^\circ / \cos 22\frac{1}{2}^\circ$ or 1.07; the effective moment of the actuating pin 27' would shift in the ratio of $\cos 14\frac{1}{3}^\circ$ to $\cos 29\frac{1}{3}^\circ$ or 1.11 and the moment of the lever's own weight from zero to that corresponding to a 15° deflection out of the horizontal, that is, from zero to the product of the weight of the lever, into the vertical offsetting 73 (Figure 10) of the pivotal axis from the lever's own center of gravity into 0.259, the sine of 15°.

As a result, in the prior art structure of Figure 10, the low weight emergence line 77, which is the low-water level for theoretical valve balance, the line downwardly beyond which any further fall of the water level will, except for the retarding effect of friction, cause the lever to shift to its open valve position, and the high-weight submergence line 78, which is the high water level for theoretical valve balance and the line upwardly beyond which any further rise of water will, except for the retardation of friction, cause the lever to shift into its open valve position, have been readily shifted by shifting the initial closed-valve position of the lever, for example by small changes in the height of the valve seat 76. Thus the use of a thicker washer 79 for example under the valve seat 76 would favor the low weight 41' as compared to the high weight 40' and thereby upwardly shift the low-weight emergence line 77 of theoretical valve balance and correspondingly downwardly shift the high-weight submergence line 78 of theoretical valve balance.

While the prior art structure has thus had great advantages that have deservedly resulted in its commercial success and wide use it has nevertheless inadequacies that have been pro-

gressively greater with progressively higher pressures, and at very high pressures have been so great as to make the device even inoperative, and a particular object of the present invention therefore has been to provide a device suited to use with very high pressures, and at any pressures to be more sensitive than the devices of the prior art.

This has been accomplished by locating the fulcrum 26 of the lever and the axes of the low and high weight suspension pivots 42 and 43 on a common line 80 (Figure 11), by locating the actuating pin 27 very close to the lever axis 26 and preferably on the line 80, and by reducing friction by the use of knife edges at the low and high weight suspension pivots 42 and 43.

In both the structure of Figure 11 and that of Figure 10, when the lever 24 is in its normal valve-closed position, with the water level intermediate the low and high water levels 77 and 78, the turning moments toward closure exerted by the high weight 40 or 40' and by the stream pressure pressing the valve to its seat, overbalance the opening turning moments exerted by the low weight 41 or 41' and by the weight of the valve mechanism.

At each of the low and high water levels 77 and 78 for valve balance, these moments are relatively equal and for both structures the fraction w_2 of submergence of the low weight 41 or 41' at the low water level 77 for valve balance could be expressed as a relation $w_2 = R_2 / (D_w - D_s)$ and the fraction S' presented to steam by the high weight 40 or 40' as a relation $S' = R_1 / (D_w - D_s)$. In these expressions D_w and D_s are the weights per cubic foot respectively of water and of steam at the given operating conditions, and the maximum change in the downward pull of either weight is measured by $(D_w - D_s)$ times the cubic feet volume V of the weight. R_1 and R_2 are factors depending upon the design and the steam conditions and, with the prior art structure, depending also upon the selected position of the levers for valve closure.

In both structures R_1 and R_2 change with change in the steam pressure within the water-column and with the Figure 10 prior art structure the degree and character of such changes at very high pressures make the operation indefinite and unreliable and in fact make structure that is very satisfactory at low and moderate pressures inoperative at very high pressures. The downward off-setting of the laterally offset actuating pin 27 in the prior art structure which at low pressures is to some degree advantageous, becomes at very high pressures in every way disadvantageous and the same is true, though probably to lesser degree, with respect to the upward offsetting of the pivot axis 26' from the line 72 joining the axes of the suspension pivots 42 and 43.

The value of $(D_w - D_s)V$ for a given size V of weights is about one third less at 1500 pounds per square inch pressure than at say 100 pounds per square inch pressure, while the upward closure force exerted by the steam pressure upon the valve for a given valve port is fifteen times as great. The first factor, for a given size of weights 40' and 41', reduces the available actuating force by one third, and the second factor for a given location of the actuating pin 27' and given size of valve port 25', greatly increases the needed actuating force beyond that needed at moderate pressures, and thereby, for any given type of bearing greatly increases the friction.

For this reason the type of bearings at 42 and 43 satisfactory at low and moderate pressures become unsatisfactory at very high pressures because at such pressures the needed actuating force has been increased by the greater importance of the steam reaction upon the needle valve, while the available actuating force for a given weight volume has been materially diminished by the fall in the value of $(D_w - D_s)$, so that for use at very high pressures the requisite volume V and therefore the weight to be supported by the lever needs to increase beyond that quite adequate at low or moderate pressures.

The same orifice may be used for the entire pressure range. The device has been found to operate quite successfully on an orifice of only one-thirty second inch diameter. For the lower ranges, however, somewhat larger orifices become desirable because of danger of clogging and I have successfully tested these devices using orifices of one-sixteenth inch diameter for the range of 100 to 500 pounds pressure and three sixty-fourths inch diameter for the range from 500 to 800 pounds pressure.

In the structure of Figure 11, intended to be suited to any usual pressures, whether very high or low, the greater importance at high pressures of the steam reaction upon the needle valve and the falling away of the term $D_w - D_s$ are counteracted by replacing the pin bearings with knife edge bearings and the importance itself of the steam reaction upon the needle valve is lessened by bringing the actuating pin very close to the axis 26 of the lever.

In the prior art structure, the values of R_1 and R_2 are very different for the selectively different angular positions of the lever at valve closure, and this variance of R with angularly different initial settings of the lever is avoided in the structure of Figure 11 by making the lever axis 26 and the weight suspension axes 42 and 43 on a common line 80. The actuating pin 27 also is preferably on this line, since R is then quite independent of small variations in the initial settings of the lever.

The values of R_1 and R_2 for the structure of Figure 10 are in complex functional relations with the initial angular setting of the balance, which differently vary the moment arms of the weights and also the moment of the steam reaction from the closure pressure on the needle valve.

In the illustrated structure of Figure 11, however, with the lever pivot 26, the actuating pin 27 and the suspension pivots 42 and 43 on a common line 80, and the weights 40 and 41 of equal volume, the terms R_1 and R_2 are independent of the initial angular setting of the lever, are relatively equal and numerically equal to $(W - PA) b / Va$ in which b/a is the ratio of actuating pin moment arm b to either weight moment arm a , V is the volume of either weight in cubic feet, P is the pressure within the alarm column in pounds per square inch, A is the area of the valve port closed by the valve in square inches, and W is a weight in pounds assumed in the formula to be applied at the actuating pin 27 and therefore having a moment arm b . In actual practice W includes the weight of the valve mechanism at the actuating pin, with a moment arm b , and the other weight corrected to a moment arm a , and suitably applied to the T bar 51 or upon the low weight suspension chain at a portion thereof above the water, or, perhaps less desirably, it may be applied as an increase in the weight 41.

itself, this however upsetting the assumption of equality of volumes of the two weights, making R_1 and R_2 no longer quite equal, the requisite total weight upon the levers being somewhat greater with a somewhat greater friction and therefore lower sensitiveness.

With the foregoing assumptions, according to theory:

$$10 \quad S_1 = w_2 = \frac{b(W - PA)}{aV(D_w - D_s)}$$

which, always less than unity, can be selected to give any desired value for w_2 , assuming known values of $(D_w - D_s)$, so that for example if the values of W and A are related to give w_2 a value of 0.5 at low pressure conditions of say 100 pounds per square inch pressure with $(D_w - D_s)$ about say 56 and to give w_2 a value of 0.5 at high pressure conditions of say 1500 pounds per square inch pressure with $(D_w - D_s)$ about, say 38, the value of w_2 at all intermediate pressure conditions will be adequately close to 0.5.

The figures above are not reached in commercial operation because of the fact that their attainment would require very large weights, and these of course cannot be used commercially.

Quite satisfactory results have been obtained with a difference of weight between the two weights and their suspensions of approximately 30 $\frac{1}{2}$ pound and with orifice diameters as follows:—

	Pounds pressure
1 $\frac{1}{8}$ " from	100 to 500
3/64" from	500 to 800
32" from	800 to 1500

35 In these tests the lower weight approximated three inches in diameter and three inches in length, and the upper weight was similar in shape and nearly the same size, the weight difference appearing largely in the weights of their suspensions.

It will be understood that the values of $(D_w - D_s)$ in practice change with concentration of salts or other impurities in the boiling water, being normally relatively high just before each blow-off of the boiler, so that the line 11, Figure 11, for valve balance, will be lower as the concentration of dissolved solids increases.

While the invention finds its best embodiment in a device using a steam whistle as the alarm, it 50 will be understood that it is also applicable to a device using some other type of alarm, thrown by movement of the member.

In view of my invention and disclosure variations and modifications to meet individual whims or particular need will doubtless become evident to others skilled in the art to obtain all or part of the benefits of my invention without copying the structure shown and I therefore claim all such in so far as they fall within the reasonable 60 spirit and scope of my invention.

Having thus described my invention, what I claim as new and desire to secure by Letters Patent is:—

1. In an alarm water column, high-water and 65 low-water weights, operating levers fulcrumed at their middles, upwardly directed knife-edges pivotally suspending the weights from near the lever ends, an actuating pin on each lever adjacent the fulcrum and means for operating an alarm in response to motion of the actuating pins, the fulcrum of the levers being substantially on the line through the knife-edge suspensions of the 70 weights.

2. In an alarm water column, high-water and

low-water weights, actuating levers fulcrumed at their middles, upwardly directed knife-edges pivotally suspending the weights from near the lever ends, an actuating pin on each lever adjacent the fulcrum and means for operating an alarm in response to motion of the actuating pins, the fulcrum of the levers and the actuating pins of each lever being substantially on the line connecting the knife-edge suspensions of the 10 particular lever.

3. In an alarm water column, a pair of levers fulcrumed at their middles on a knife edge, high water and low-water weights, suspensions for the weights from the levers, spacing means for the levers having convexly curved surfaces closely adjacent the fulcrum for spacing the weights with minimum friction and means operatively connecting the levers with an alarm.

4. In an alarm water column, an operating lever having a knife-edge fulcrum at its middle, 20 having a spacing lug above and immediately adjacent to the knife edge fulcrum on the side adjoining a cooperating lever, having knife-edge suspensions at the ends of the lever and having an actuating pin adjacent the knife-edge fulcrum. 25

5. In an alarm water column, an operating lever having a knife-edge fulcrum at its center, having a spacing lug above and immediately adjacent to the knife-edge fulcrum on the side adjoining a cooperating lever, having knife-edge 30 suspensions at the ends of the lever and having an actuating pin adjacent the knife-edge fulcrum, the knife-edge fulcrum, actuating pin and knife-edge suspensions all being on the same line.

6. In an alarm water column, the combination 35 of a pair of levers each having an opening near its center, a common central knife-edge fulcrum for the levers, the levers having spacing lugs extending toward one another above and adjacent to the fulcrum, actuating pins on the levers on respectively opposite sides of the fulcrum, a valve actuating yoke operatively engaging the actuating pins between the levers and pivotal weight suspensions on the ends of the levers.

7. In an alarm water column, the combination 45 of a pair of levers each having an opening near its center, a common central knife-edge fulcrum for the levers, the levers having spacing lugs extending toward one another above and adjacent to the fulcrum, actuating pins on the levers on respectively opposite sides of the fulcrum, a valve-actuating yoke operatively engaging the actuating pins between the levers and pivotal weight suspensions on the ends of the levers, the central 50 knife-edge fulcrum, actuating pin and weight suspensions for each lever all being substantially on a line.

8. In low and high water alarm mechanism for use with a boiler or the like, a casing in communication at high and low portions thereof with the water and steam spaces respectively of the boiler, a stationary horizontal fulcrum within the casing at a high portion thereof, a pair of laterally spaced levers centrally mounted upon and turning on the fulcrum, horizontal upwardly directed 60 knife-edge weight suspension pivots near the ends of the levers, a high-water weight below the fulcrum having at one side suspension from one of the weight suspension pivots of one lever and at the other side suspension from the opposite 65 weight suspension pivot of the other lever, a low-water weight spaced below the high-water weight and having suspension from the remaining weight suspension pivots, one of each lever, a yoke vertically above the common pivot, having 70 75

downwardly depending arms spanning the fulcrum and having oppositely directed horizontal slots therein, one in each arm, an actuating pin on each lever to the side thereof supporting 5 the low-water weight and fitting one of the oppositely directed horizontal slots of the yoke and an alarm mechanism operated by the yoke, the weight suspension pivots being located with respect to one another and to the fulcrum so that 10 the line cross-connecting the weight suspension pivots of each lever will pass substantially through the fulcrum.

9. In low and high water alarm mechanism for use with a boiler or the like, a casing in communication at high and low portions thereof with the water and steam spaces respectively of the boiler, a stationary horizontal fulcrum within the casing at a high portion thereof, a pair of laterally spaced levers centrally mounted upon and 20 turning on the fulcrum, horizontal upwardly directed knife-edge weight suspension pivots near the ends of the levers, a high-water weight below the fulcrum having at one side suspension from one of the weight suspension pivots of one lever 25 and at the other side suspension from the opposite weight suspension pivot of the other lever, a low-water weight spaced below the high-water weight and having suspension from the remaining weight suspension pivots, one of each lever, a yoke vertically above the common pivot, having 30 downwardly depending arms spanning the fulcrum and having oppositely directed horizontal slots therein, one in each arm, an actuating pin on each lever to the side thereof supporting the low-water weight and fitting one of the oppositely directed horizontal slots of the yoke and an alarm mechanism operated by the yoke, the weight suspension pivots and the actuating pins being located with respect to one another and to the 35 fulcrum so that the line cross-connecting the weight suspension pivots of each lever will pass substantially through the fulcrum and the actuating pin center.

10. In low and high water alarm mechanism for use with a boiler or the like, a casing in communication at high and low portions thereof with the water and steam spaces respectively of the boiler, a stationary horizontal fulcrum within the casing at a high portion thereof, a pair of laterally spaced levers centrally mounted upon and turning on the fulcrum, horizontal upwardly directed knife-edge weight suspension pivots near the ends of the levers, a high-water weight below the fulcrum having at one side suspension 40 from one of the weight suspension pivots of one 45

lever and at the other side suspension from the opposite weight suspension pivot of the other lever, a low-water weight spaced below the high-water weight and having suspension from the remaining weight suspension pivots, one of each lever, a yoke vertically above the common pivot, having 5 downwardly depending arms spanning the fulcrum and having oppositely directed horizontal slots therein, one in each arm, an actuating pin on each lever to the side thereof supporting the 10 low-water weight, close to the fulcrum and fitting one of the oppositely directed horizontal slots of the yoke and a steam whistle including a needle valve operated by the yoke, the weight suspension pivots and the actuating pins being located with 15 respect to one another and to the fulcrum so that the line cross-connecting the weight suspension pivots of each lever will pass substantially through the fulcrum and the actuating pin center.

11. In low and high water alarm mechanism for use with a boiler or the like, a casing in communication at high and low portions thereof with the water and steam spaces respectively of the boiler, a stationary horizontal fulcrum within the casing at a high portion thereof, a pair of laterally spaced levers centrally mounted upon and turning on the fulcrum, horizontal weight suspension pivots near the ends of the levers, an axially perforated high-water weight below the fulcrum having at one side suspension from one of the 30 weight suspension pivots of one lever and at the other side suspension from the opposite weight suspension pivot of the other lever, a low-water weight spaced below the high-water weight, a suspension for the low-water weight from the 35 remaining weight suspension pivots including a T bar extending through the perforation in the high-water weight, the cross bar of the T bar being axially bored and bevelled at the ends and the bores receiving pins to secure the suspensions 40 to the T bar, a yoke vertically above the common pivot, having downwardly depending arms spanning the fulcrum and having oppositely directed horizontal slots therein, one in each arm, an actuating pin on each lever to the side thereof supporting the low-water weight and fitting one of the oppositely directed horizontal slots of the yoke and an alarm mechanism operated by the yoke, the weight suspension pivots being located with respect to one another and to the 45 fulcrum so that the line cross-connecting the weight suspension pivots of each lever will pass substantially through the fulcrum.

WALTER J. KINDERMAN.
